VARIABLE DISPLACEMENT PUMP

Ralph M. Heintz, Cleveland, Ohio, assignor to
Jack & Heintz, Inc., Cleveland, Ohio

Application January 5, 1942, Serial No. 425,595

5 Claims. (Cl. 103—37)

My invention relates to variable displacement pumps, and more particularly to a pump whose output can be varied while it is operating.

Among the objects of my invention are: To provide a simple and efficient variable displacement pump; to provide a pump whose displacement may be varied from zero to maximum output; to provide means for varying the displacement of a pump while operating, and to provide a means for changing the timing of one piston with relation to another in a variable displacement pump.

Referring to the drawings:

Figure 1 is a longitudinal view partly in section and partly in elevation taken through a variable displacement pump utilizing my invention;

Figure 2 is a view similar to Figure 1, indicating a change in timing of the pistons of the pump of Figure 1;

Figure 3 is a view partly in elevation and partly in section taken as indicated by the line 3—3 in Figure 2;

Figure 4 is a diagrammatic view of a radial 6-cylinder variable displacement pump;

Figure 5 is a diagrammatic view of a 4-cylinder V-type pump;

Figure 6 is a diagrammatic view of the drive shaft and eccentrics of a 6-cylinder radial pump as shown in Figure 4.

Figure 7 is a fragmentary view partly in section and partly in elevation of a modification of my device using external gear teeth on the eccentrics.

Figure 8 is a fragmentary view, partly in section and partly in elevation, of another modification of my device.

My invention comprises a variable displacement pump, using two eccentrics and two pistons, driven by the same shaft, together with means whereby both of the eccentrics may be rotated in opposite directions with respect to the shaft, so that the pistons may be timed to reciprocate either in-phase or 180° out-of-phase. All degrees of phase difference between these limits may be obtained, and if the cylinders in which the pistons operate are interconnected, the device, when used as a pump, will have a complete range of output from zero to the maximum displacement of both pistons.

In the ensuing specification the word eccentric is deemed to be fully equivalent to any form of eccentric, crank, cam or similar structure which will change rotary motion into reciprocating motion of the piston. Furthermore, the word pis-

ton as broadly used herein is deemed to include cylindrical pistons directly driven by cams as well as pistons which may be driven from eccentrics or cranks by means of connecting rods. The diaphragm type of piston is also included in the term.

My invention may be more fully understood by describing it in connection with the drawings:

In Fig. 1, a cylinder casting 1 is provided with 10 side-by-side cylindrical bores 2 and 3 in which pistons 4 and 5 are mounted for reciprocation. The central division 6 between the two cylinders is provided with an aperture 7 above the top of the strokes of the pistons, interconnecting the cylinder head spaces 9 and 10. Aperture 7 is of such an area that the entire displacement of one piston may be passed through the aperture to the head space of the other piston without substantial flow resistance. The top of the cylinder block is closed by cylinder head 11 in which an inlet valve 12 and an outlet valve 14 is mounted, the inlet valve 12 being enclosed by inlet pipe 15 and the outlet valve 14 being enclosed by an outlet pipe 16. These valves may be of any conventional design, spring controlled or positively driven. The capacity of the pump comprising both cylinders is dependent upon the stroke relation of the two pistons 4 and 5. In the device of Fig. 1 I drive pistons 4 and 5 by connecting rods 17 and 18 respectively, these rods terminating in eccentric bearings 20 and 21 respectively, mounted on eccentrics 22 and 23. Eccentrics 22 and 23 are provided with eccentric apertures, these apertures being helically slotted to form an internal helical gear. Drive shaft 24 has spaced helical gears 25 and 26 cut thereon, the gearing being in an opposite direction as between the two gears 25 and 26. The eccentrics 22 and 23 are mounted on gears 25 and 26, respectively. Thus shaft 24 may move axially along the gear teeth with respect to eccentrics 22 and 23 but the latter are at all times coupled with shaft 24 for rotation thereby by the intermeshing of the helical gear teeth on shaft and eccentric. Shaft 24 is supported centrally by a central web bearing 27 carrying a sleeve bearing 28. I prefer to mount web bearing 27 on a crank case 29 which is fastened to cylinder block 1 along the horizontal plane intersecting the axis of shaft 24 assuming the pump is vertically positioned. Thus all the shaft bearings become split bearings and the shaft may be easily assembled in the pump. Sleeve bearing 28 is provided with end flanges 55 30 bearing against the inner surface of each ec-

centric 22 and 23, and is freely rotatable on web bearing 27.

Outside of one eccentric in this modification, the shaft 24 terminates in a stub end 31, which ends in an oil chamber 32. The other end of the shaft 24 terminates in a splined end 34 to which is applied an internally splined power shaft 35 to which is attached a drive pulley 36, this drive pulley being provided with a thrust bearing 37 carried on a bearing hanger 38 to absorb end thrust. It should be fully understood that while I have shown plain bearings throughout the structure, roller or ball-bearings may be utilized for absorbing both rotatable and thrust friction wherever deemed necessary. Inasmuch as power shaft 35 is larger than splined end 34 of shaft 24 an oil chamber 40 will be formed around splined end 34, thus exposing a pressure shoulder 41 on the left hand end of gear 24. Oil chamber 40 is supplied with oil through an oil pipe 42 passing through a reversible pump 44, the oil then passing through oil line 45 to oil chamber 32 at the other end of the shaft. Eccentrics 22 and 23 are maintained as to outward movement by outer bearings 46 and 47, respectively. As thus mounted eccentrics 22 and 23 are maintained in proper axial position to rotate their pistons 4 and 5 through connecting rods 17 and 18. However, the entire shaft 24 is capable of axial movement in accordance with the differential oil pressures exerting against the opposite ends of shafts 24 by reversible pump 44, and due to the spline connection with drive shaft 35 can be rotated in any axial position.

I prefer to rotate the structure shown in Fig. 1 in a direction which will cause eccentrics 22 and 23 to exert their thrust against sleeve bearing 28, which is free to rotate in web bearing 27. Inasmuch as, under normal circumstances, both eccentrics rotate together and in synchronism, sleeve bearing 28 will rotate with the eccentrics. As the thrust will be equal and opposite against sleeve bearing 28 will rotate with the eccentrics, in any bearing. When shaft 24 is in the position shown in Fig. 1, both pistons will rise and fall together and consequently the output of the pump will be that of the additive displacements of both pistons; i. e., maximum output of the pump.

If, however, by means of reversible pump 44, shaft 24 is axially moved, the eccentrics 22 and 23 will be rotated on the helical gears with respect to shaft 24, and when shaft 24 has been moved to the left for example, as far as it need travel, the eccentrics 22 and 23 will be 180° out-of-phase and the pistons will also be similarly out-of-phase. Inasmuch as the opening 7 will carry the complete displacement of either piston, the contents of the cylinders will be simply transferred from one cylinder to the other, back and forth, and there will be no appreciable output pressure developed. This position corresponds to the zero delivery of the pump, and is shown in Fig. 2. The reversible pump 44 can be utilized to axially position shaft 24 in any intermediate stage between full pump output and zero output. Thus, the combination of the two cylinders becomes a pump which can be varied as to displacement, from zero delivery to maximum delivery. Furthermore, any such change in displacement may be accomplished while the pump is running. Thus the pump I have described is ideally adapted for use, for example, in supplying hydraulic pressure which can be used to feed oil to a

Diesel engine in metered amounts, to control gun turrets, astronomical telescopes or other heavy machinery where delicate adjustment of delivery is desired.

5 Other uses will suggest themselves to those skilled in the art. While I have described my device as using hydraulic control of the axial position of shaft 24, I wish it distinctly understood that direct mechanical control may be 10 easily accomplished without interfering with the broader aspects of my invention.

In Figs. 4 and 5 and 6, I have shown how a multiple cylinder assembly may be driven from the same shaft.

15 In Fig. 4 I have shown a 6-cylinder arrangement with three pairs of cylinders. In this case the shaft 24 has three eccentrics 22, and three eccentrics 23, mounted on helical gears 25 and 26, respectively. Each of the eccentrics 22 drives one of the pistons in each cylinder pair, with eccentrics 23 driving the other of the pistons in each pair. Each pair of cylinders is provided with inlet and outlet pipes 15 and 16 as in Fig. 1, which are then joined to form inlet and outlet manifolds 50 and 51. Each pair of cylinders 2-3 also includes inlet and outlet valves 12 and 14, and the interconnecting aperture 7. The axial position of shaft 24 is controlled as in the device of Figs. 1 and 2.

20 Fig. 6 illustrates the relative positions of the three eccentric bearings 20, and the three eccentric bearings 21, on the respective helical gears 25 and 26, this figure being an enlarged fragmentary view taken at right angles through Fig. 30 4 to correspond to Fig. 1. If the shaft 24 and its gears 25 and 26 are shifted to the left, as in Fig. 2, the three eccentrics 22 and their eccentric bearings 20 will be shifted angularly in one direction, while the three eccentrics 23 and their eccentric bearings 21 will be shifted angularly an equal amount in the opposite direction, in the same manner as the pair of single eccentric and bearing combinations 22, 20 and 23, 21 in Fig. 2, it being understood that means (not shown) 45 are provided in Fig. 6 as in Figs. 1 and 2 to prevent axial movement of the eccentrics. From the above description it is obvious that more than three pairs of cylinders may be arranged in radial fashion about the drive shaft, if desired.

50 Fig. 5 is a 4-cylinder arrangement similar to Fig. 4, except in this case only two eccentrics 22 and 23 need be mounted on each helical gear 25 and 26. The eccentric 22 will operate a piston in each of the two cylinders 2, and the eccentric 55 23 will operate a piston in each of the two cylinders 3. One pair of cylinders 2-3 then forms a right bank and the other pair of cylinders 2-3 forms a left bank, each pair being provided with an interconnecting aperture 7, inlet and outlet 60 valves, and inlet and outlet pipes connected into the manifolds 50 and 51. Other cylinder arrangements of my invention will readily suggest themselves to those skilled in the art.

In Figs. 7 and 8 I have shown alternative shaft 65 and eccentric gear connections. In Fig. 7 connecting rods 17 and 18 are driven by crank pins 52 and 54 which are attached to the inner surface of externally cut helical gears 55 and 56. The helical gears 55 and 56 are mounted on stub 70 shafts 57 and 58 respectively, and these stub shafts are provided with central bearings 60 and 61, respectively, to absorb thrust. A drive shaft 24 is then provided, rotation and axial movement being provided for in a fashion similar to 75 that described in conjunction with Figs. 1 and

2, the helical gears 25 and 26 meshing externally with gears 55 and 56.

In this case the gears can be rotated in either direction desired but of course the thrust friction must be taken up by suitable thrust bearings as the cranks are between the two gears 55 and 56.

In Fig. 8, however, I have shown a crank operated device wherein the sleeve bearing 28 is utilized. Here the sleeve bearing 28 may be split longitudinally and centrally provided with an annular channel 62 to receive flanges 63 on the end of stub shafts 57 and 58. If shaft 24 in this modification is then rotated in a direction to force the helical gears 55 and 56 together, the thrust will be taken by sleeve bearing 28 as in the modification shown in Figs. 1 and 2. In the modification of Fig. 8, the flanges 63 position the helical gears during relative movement, and absorb thrust in case the pump rotation is reversed.

My invention is capable of still further modifications. Changes, therefore, in the construction and arrangement may be made which do not depart from the spirit and scope of the invention as defined in the appended claims.

I claim:

1. A variable displacement pump comprising a pair of adjacent cylinders, a piston in each cylinder, the space above said pistons being interconnected to form a pump chamber, inlet and outlet valves in the walls of said pump chamber, an eccentric connected to operate each piston, a drive shaft, a pair of helically threaded members rotated by said shaft, the threads on said members being oppositely pitched, helical threads on each of said eccentrics meshing with one of said members, means for axially moving said shaft with respect to said eccentrics, and means for rotating said shaft, said axially moving means comprising external hydraulic control means arranged to apply hydraulic pressures selectively on opposed cross sectional areas of said shaft.

2. A variable displacement pump comprising a pair of adjacent cylinders, a piston in each cylinder, the space above said pistons being interconnected to form a pump chamber, inlet and outlet valves in the walls of said pump chamber, an eccentric connected to operate each piston, a drive shaft, a pair of helically threaded members rotated by said shaft, the threads on said members being oppositely pitched, helical threads on each of said eccentrics meshing with one of said members, external hydraulic control means for axially moving said shaft with respect to said eccentrics, and means for rotating said shaft comprising a coaxial power shaft fixed as to axial movement and splined to one end of said drive shaft, said axially moving means including a sealed space between a cross-sectional area of said drive shaft and a cross-sectional area of said power shaft, the opposite end of said drive shaft entering a second sealed space, together with means for supplying controlled hydraulic pressures to said spaces.

3. A variable displacement pump comprising a plurality of pairs of adjacent cylinders arranged radially about a drive shaft, pistons in said cylinders, inlet and outlet valves in communication with each pair of cylinders, a free communicating passageway connecting the cylinders of each pair, inlet and outlet manifolds connected with each pair of cylinders, a plurality of

eccentric means driven by said drive shaft for operating said pistons, and adjustable means for shifting the relative angular positions of said eccentric means so as to simultaneously vary the phase positions of the pistons in each pair of cylinders to vary the displacement of the pump, said adjustable means comprising a pair of helically threaded members rotated by said shaft, the threads on said members being oppositely pitched, helical threads on said eccentric means meshing with said members, external hydraulic control means for axially moving said shaft with respect to said eccentrics, and means for rotating said shaft comprising a coaxial power shaft fixed as to axial movement and splined to one end of said drive shaft, said axial moving means including a pressure shoulder on said drive shaft, an oil chamber surrounding a portion of said drive shaft between said pressure shoulder and an end of said power shaft, an oil chamber containing the opposite end of said drive shaft, and means for supplying controlled hydraulic pressures to said oil chambers selectively.

4. A variable displacement pump comprising a pair of adjacent cylinders, a piston in each cylinder, the space above said pistons being interconnected to form a pump chamber, inlet and outlet valves in the walls of said pump chamber, an eccentric connected to operate each piston, a drive shaft, a pair of helically threaded members rotated by said shaft, the threads on said members being oppositely pitched, helical threads on each of said eccentrics meshing with one of said members, external hydraulic control means for axially moving said shaft with respect to said eccentrics, a web between said cylinders, a web bearing in said web, and a sleeve bearing freely rotatable in said web bearing and having end portions abutting said eccentrics to receive and tend to neutralize opposing thrusts therefrom to reduce thrust friction in the operation of the pump.

5. A variable displacement pump comprising a pair of adjacent cylinders, a piston in each cylinder, the space above said pistons being interconnected to form a pump chamber, inlet and outlet valves in the walls of said pump chamber, an eccentric connected to operate each piston, a drive shaft, a pair of helically threaded members rotated by said shaft, the threads on said members being oppositely pitched, helical threads on each of said eccentrics meshing with one of said members, external hydraulic control means for axially moving said shaft with respect to said eccentrics, a web between said cylinders, a web bearing in said web, a sleeve bearing freely rotatable in said web bearing and having end portions abutting said eccentrics to receive and tend to neutralize opposing thrusts therefrom to reduce thrust friction in the operation of the pump and means for rotating said shaft comprising a coaxial power shaft fixed as to axial movement and splined to one end of said drive shaft, said axially moving means including a pressure shoulder on said drive shaft, an oil chamber surrounding a portion of said drive shaft between said pressure shoulder and an end of said power shaft, an oil chamber containing the opposite end of said drive shaft, and means for supplying controlled hydraulic pressures to said oil chambers selectively.

RALPH M. HEINTZ.
